LOUIS VINGHEROETS, OF GRAND RAPIDS, MICHIGAN, ASSIGNOR TO DOW GAS ENGINE STARTER CORPORATION, OF WILMINGTON, DELAWARE, A CORPORATION OF DELAWARE

STARTER FOR INTERNAL-COMBUSTION ENGINES

Application filed October 14, 1927. Serial No. 226,219.

This invention relates to starter mechanisms for internal combustion engines and has as its general object to provide a starter mechanism which will overcome the disadvantages presented by such mechanisms as ordinarily constructed.

In the ordinary starter mechanism, a pinion is fixed upon the starter shaft and meshes with teeth upon the fly wheel of the internal combustion engine, but this means for transmitting power from the starter shaft to the fly wheel presents several disadvantages. In the first place, the teeth of the pinion and the teeth upon the fly wheel are subjected to severe strain, even in the normal operation of the mechanism, and in event of the spark being too far advanced, resulting in a back fire of the engine, it is almost certain that a number of the gear teeth will be broken off, thus necessitating replacement of the fly wheel. Furthermore, in many instances, under the conditions referred to, the armature shaft is sprung, thus necessitating expensive repairs and replacements. Likewise, the transmission of power from the starter shaft to the fly wheel through the medium of gears is attended by considerable noise and therefore the present invention has, as its more specific object, to overcome these difficulties by the provision of a starter mechanism which will transmit power to the fly wheel without any likelihood of damage to any of the parts in the event of back firing of the engine.

Another disadvantage presented by starter mechanisms of the usual construction as, for example, the well known Bendix drive, is that the mechanism is complicated and liable to have its parts disarranged or damaged in the event of back fire of the engine or in the event of longitudinal shifting of the fly wheel shaft or an uneven rotation of the fly wheel, and therefore the present invention has as a further object to provide a starter mechanism which will present none of these disadvantages but will, on the other hand, be extremely simple and durable in construction and capable of efficient operation even though there be a longitudinal play of the fly wheel shaft or a slight uneven rotation thereof.

While the starter mechanism embodying the invention is, as stated, so constructed that the parts will not be liable to become disarranged or damaged, the invention contemplates as a further object, the provision of a mechanism comprising an assemblage and arrangement of parts such as to permit of repairs or replacements being readily effected in the event they should be found necessary.

While the accompanying drawings and the description which is to follow, constitute a disclosure of the preferred embodiment of the invention, it will be understood that various changes may be made within the scope of what is claimed.

In the accompanying drawings:

Figure 1 is a view in side elevation of the starter mechanism embodying the invention, the fly wheel with which the mechanism is associated, being shown in vertical section;

Figure 2 is a vertical longitudinal sectional view through the mechanism, the shaft of the starter motor being shown in elevation;

Figure 3 is a top plan view of the mechanism;

Figure 4 is a vertical transverse sectional view taken substantially on the line 4—4 of Fig. 1 looking in the direction indicated by the arrows;

Figure 5 is a similar view on the line 5—5 of Fig. 1 looking in the direction indicated by the arrows;

Figures 6, 7, 8 and 9 are perspective views of component parts of the mechanism disassembled.

In the drawings the shaft of the starter motor is indicated by the numeral 1 and does not differ essentially from the ordinary construction, and the flywheel is indicated by the numeral 2 and differs from the ordinary fly wheel, which is provided with peripheral gear teeth, in that it is provided with a peripheral bead 3 or driven member having its side faces beveled so as to provide friction surfaces for a purpose presently to be explained.

The numeral 4 indicates a sleeve which is formed with a bore 5 adapting it to snugly and yet slidably fit the shaft 1, and this sleeve is provided at its outer end with a circular

head 6 having a beveled friction face 7 or driving member which is designed to coact with one driving of the friction faces of the bead 3, under conditions to be presently explained, the sleeve 4 normally occupying the position shown in Fig. 1 of the drawings, in which position the face 7 of the head 6 is slightly spaced with respect to the adjacent beveled face of the bead 3, the head 6 constituting one driving member and the other driving member being indicated in general by the numeral 8. The clutch member 8 comprises a sleeve 9 which is rotatably and slidably fitted onto the sleeve 4 and is provided, at its end which opposes the head 6, with a head 10, which, as in the case of the head 6, is circular and is provided with a beveled friction face 11 which opposes the friction face 7 of the head 6 and is designed to coact with the other beveled friction face of the bead 3 of the fly wheel 2, under conditions to be presently pointed out, the sleeve 8, however, normally assuming the position shown in Fig. 1 of the drawings, in which position its friction face 11 is out of contact with the coacting friction face of the bead 3. A compression spring 12 is arranged upon the sleeve 4 and bears at its ends against the friction faces 7 and 11 of the heads 6 and 10, at the inner peripheries of these faces, the spring being more or less snugly fitted upon the sleeve 4, so as not to come in contact with the periphery of the bead 3. At its end opposite its end at which the head 10 is located, the sleeve 9 of the member 8 is formed with a helical cam face 13 which extends nearly throughout the circumference of the sleeve, the formation of this face resulting in an abrupt shoulder 14 which is straight and parallel to the axis of the sleeve, and a projection 15 at the said end of the sleeve between the ends of the cam face 13 and having one side coextensive with the shoulder 14.

A collar 16 is fitted onto a portion of the sleeve 4, and this portion is reduced so as to provide a circumscribing shoulder 17 against which one end of the collar abuts, the collar being formed at this end with a circumscribing reinforcing flange 18 from which projects a longitudinal lug 19 one side of which is straight and arranged to abut against the shoulder 14 of the sleeve 9, in one position of the parts as shown in Figures 3 and 5 of the drawings, the end of the lug being formed to provide a cam surface 20 which impinges against the cam face 13 of the sleeve 9. A second collar 21 is fitted onto the reduced end of the sleeve 4 and is secured in place by a set screw 22 which is threaded through an opening 23 formed in the said collar and engages, at its inner end, in an opening 24 formed in the said reduced portion of the sleeve 4.

A lock washer 25 is preferably provided upon the set screw 22 to coact therewith and

with the collar 21 to prevent backward rotation of the set screw, and at this point it will be understood that the collar 21 is in this manner connected with the reduced portion of the sleeve 4, so as to be rotatable therewith under conditions to be presently described. The collar 16 is formed with diametrically oppositely located recesses 26, in its end opposite its end at which the lug 19 is located, and the collar 21 is provided with diametrically oppositely located tongues 27 which engage in the recesses 26, in a manner clearly shown in Figs. 1 and 3 of the drawings, so as to connect the collars 16 and 21 for rotation in unison. It will be observed by reference to Figs. 1, 2 and 7 of the drawings that the tongues 27 are of a thickness less than the thickness of the wall of the collar 21, so that their outer sides will be flush with the outer surface of the collar 16, which collar is of less circumference than the collar 21. A compression spring 28 is arranged upon the collar 16 and bears at one end against the inner side of the circumferential rim 18 thereon and at its other end against the adjacent end of the collar 21, this spring tending normally to hold the collar 16 shifted forwardly upon the sleeve 4 and with its forward end in abutting engagement with the shoulder 17.

A collar 29 is mounted upon the shaft 1 and fixed for rotation therewith by means of a key 30 and the said collar is held against longitudinal displacement upon the shaft by means of a set screw 31 which is threaded into an opening 32 in the collar and is tightened to bind at its inner end against the said shaft 1, a lock washer 33 being preferably provided for holding the set screw against accidental loosening. The collar 21 is provided in its end opposite its end at which the tongues 27 are located, with notches indicated by the numeral 34, and the collar 29 is provided with diametrically oppositely located tongues 35 which fit in the said notches 34, the collars 21 and 29 being in this manner connected for rotation in unison. A compression spring 36 is arranged upon the shaft 1 and bears between the collar 29 and the adjacent end of the sleeve 4.

In the operation of the starter mechanism the circuit is closed through the motor of the starter, thus imparting rotary motion to the shaft 1 in the direction indicated by the arrow at the left hand side of Fig. 3 of the drawings. The collar 9 is, as previously stated, fitted upon the sleeve 4, and, when rotary motion is imparted to the shaft 1, rotary motion will likewise be imparted to the sleeve 4 due to the engagement of the tongues 35 of the collar 29, in the recesses 34 on the collar 21, which latter collar is spaced with respect to the said sleeve 4, and due to the inertia of the collar 9, the sleeve 4, through the fast rotary impulse imparted to it by the shaft 1, will rotate within the collar 9, carrying with

it the collar 16 and causing the cam face 20 of the lug 19 upon said collar 16 to ride up along the cam face 13 of the said collar 9, thus shifting the collar 9 outwardly (toward the right hand side of Figure 3) along the sleeve 4 to bring the beveled friction face 11 thereof into contact with the adjacent beveled friction face of the flange of the fly wheel 2. This will likewise serve to shift the collar 6, in the opposite direction, due to the sleeve 4 and its abutment of the friction face 11 of the head 10 with the flange 3, and in this shifting movement the collar 16, will be shifted longitudinally upon the shaft 1 and 15 against the pressure of spring 28 as to bring the friction face 7 of the head 6 of said sleeve to binding frictional contact with the other beveled friction surface of the flange 3, and as a consequence the friction faces of the heads 6 and 10 will firmly grip the said flange and rotary motion will be imparted to the fly wheel in the direction indicated by the arrow at the right-hand side of Fig. 3. As soon as the engine starts to function, the 25 fly wheel 2 will of course be rotated at a greater rate of speed than the shaft 1 of the starter mechanism and, as a consequence, the collar 9 will be rotated, momentarily, at a higher rate of speed than that at which it was 30 previously rotated by the shaft 1 and the associated parts, so that the relative movement of the cams 13 and 20 will be reversed whereupon the spring 12 will act to separate the heads 6 and 10 sufficiently to cause separation of the friction faces 7 and 11 of the heads from the beveled friction faces of the fly wheel flange 3, it being understood that in the first described cycle of operation and in the movement of the heads 6 and 10 towards each other, the spring 12 was placed under compression. Therefore, immediately upon firing of the engine and rotation of the fly wheel 2, the component parts of the 40 starter mechanism will be restored to their normal relative positions. It will be understood that in the event of a back fire of the engine, no damage will be caused to the starter mechanism due to the fact that the fly wheel 2 would, under these conditions, be 45 rotated in the direction the reverse of that indicated by the arrow at the right hand side of Figure 3 and consequently the friction faces 7 and 11 of the heads 6 and 10 would be instantly separated from the beveled friction faces of the flange 3 of the fly wheel.

In practice, the fly wheel 2 may be so formed that the bead 3 will be integral therewith, or this bead may be formed separate from the fly wheel and secured thereto or to the engine shaft in any suitable manner.

The majority of makes of automobiles are equipped with a bracket extending from the starter motor and including a portion, indicated by the numeral 37 in Figs. 1, 2 and 3 55 of the drawings, which constitutes a bearing

for the outer end of the shaft 1 of the starter motor, and it will be observed that this portion serves also as an abutment for the head 6 to limit the outward movement of the sleeve 4.

It will also be understood that, as the spring 36 urges the sleeve 4 outwardly, and the spring 12 urges the collar 8 inwardly, the friction faces 7 and 11 will be maintained out of engagement with the flange or bead 3 of the fly wheel 2, while the engine is running.

The slip joint or spline 34, 35 permits both the heads 6 and 10 to be shifted axially and in unchanged relative position to accommodate any divergence of the flywheel 2 from a perpendicular position relatively to the axis of its rotation; and the interrelative axial movement of the heads 6 and 10 accommodates differences in the thickness of the flywheels' bead 3 between said heads.

Having thus described my invention what I claim as new is:

1. In a starter mechanism for internal combustion engines, a starter motor shaft, members having opposing friction faces for driving engagement with a portion of an engine fly wheel, means connecting one of said members for rotation with the shaft and coacting means upon the members for adjusting the same to driving position and effecting their rotation in unison, upon rotative movement of the shaft.

2. In a starter mechanism for internal combustion engines, a starter motor shaft, members having opposing friction faces for driving engagement with a portion of an engine fly wheel, means connecting one of said members for rotation with the shaft, means yieldably holding the members separated, and coacting means upon the members for adjusting the same to driving position and effecting their rotation in unison, upon rotative movement of the shaft.

3. In a starter mechanism for internal combustion engines, a starter motor shaft, members having opposing friction faces for driving engagement with a portion of an engine fly wheel, means connecting one of said members for rotation with the shaft, the other member being rotatable and shiftable upon a portion of the first mentioned member, and coacting means upon the members for effecting shifting of the second mentioned member and rotation of the members in unison, upon rotative movement of the shaft.

4. In a starter-mechanism for internal combustion engines, a starter motor shaft, a member upon the shaft including a sleeve fitting the shaft and a head having a friction face, means connecting the sleeve for rotation with the shaft, a second member shiftably and rotatably mounted upon the sleeve and having a friction face opposing the friction face of the first mentioned member, and coacting cam means upon the sleeve and the second men-

tioned member for overcoming the inertia of the second mentioned member upon initial rotation of the shaft and the sleeve of the first mentioned member and effecting shifting adjustment of the said second mentioned member to present the friction face thereof in coactive relation to the friction face of the first mentioned member.

5. In a starter mechanism for internal combustion engines, the combination with a starter motor shaft and a fly wheel having a peripheral portion provided with friction faces, of a member shiftable upon the shaft and having a friction face concentric to the shaft 10 and presented to one of the friction faces of the said portion of the fly wheel, a second member rotatable with respect to the first mentioned member and having a friction face concentric to the axis of the shaft and presented towards the other friction face of the 15 said portion of the fly wheel, means yieldably urging the said members in a direction to separate the same, means connecting the first mentioned member for rotation with the shaft, a member rotatable with the first mentioned member, and coacting cam means upon the last mentioned member and the second mentioned member for effecting adjustment of the second mentioned member in the direction of the friction face of the first mentioned member and for connecting the members for rotation in unison upon rotation of the shaft.

6. In a starter mechanism for internal combustion engines, the combination with a starter motor shaft and a fly wheel having a peripheral projecting portion having friction faces, of a member comprising a sleeve mounted upon the shaft and shiftable thereon, the said member further including a head having a friction face opposing one of the friction faces of the peripheral projection of the fly wheel a collar fixed upon the shaft, a collar fixed upon the said sleeve, a spring interposed between the first mentioned collar and the sleeve and yieldably urging the sleeve in an outward direction upon the shaft, coacting means upon the collars for connecting the same for rotation in unison and thereby by connecting the sleeve for rotation with the shaft, a second member comprising a collar shiftable and rotatably mounted upon the sleeve and provided with a friction face opposing the other friction face of the 40 peripheral projection of the fly wheel, a spring upon the sleeve between the friction faces of the first and last mentioned members yieldably holding the members separated and out of coactive engagement with the said 45 peripheral projection of the fly wheel, a collar mounted upon the sleeve, a shoulder upon the sleeve against which the last mentioned collar engages, a spring interposed between the last mentioned collar and the second mentioned collar, and coacting cam portions upon

the collar of the second mentioned member and the last mentioned collar for effecting shifting of the second mentioned member into engagement with the peripheral projection of the fly wheel and for connecting said member with the third mentioned collar for rotation therewith, and interlocking means upon the second and third mentioned collars for connecting the third mentioned collar with the second mentioned collar for rotation therewith.

7. In a starter mechanism for internal combustion engines, a starter motor shaft, a sleeve in splined relation thereto and having a driving member, a collar rotatably and axially movable on the sleeve and having a driving member, a second collar in splined relation to said sleeve, one of the collars having a helical cam engaging the other collar to move said driving members toward each other, an engine shaft having a driven member between and engaged by the first and second driving members, a spring pressing the second collar to cam engagement with the first collar.

In testimony whereof I affix my signature.
